UNITED STATES PATENT OFFICE.

FRANK E. JONES, OF KIRKWOOD, ILLINOIS.

DESIGN FOR A PAPER BOX.

SPECIFICATION forming part of Design No. 28,045, dated December 14, 1897.

Application filed October 16, 1897. Serial No. 655,485. Term of patent 3½ years.

To all whom it may concern:

Be it known that I, FRANK E. JONES, a citizen of the United States, residing at Kirkwood, in the county of Warren and State of Illinois, have invented and produced a new and original Design for a Paper Box, of which the following is a specification, reference being had to the accompanying drawings, forming part thereof.

10 In the drawings, Figure 1 is a view in perspective of a paper box, showing my new design. Fig. 2 is an end view thereof.

The leading feature of my design is a paper box shaped and ornamented to represent a 15 cooking stove or range.

The letter A designates the upper side, B and C the front and rear sides, and D and E the ends, of a paper box. The upper side A is ornamented with lines to represent the top 20 and lids of a stove or range, the front side B

is similarly ornamented to represent the front side and doors of the stove or range, and the ends D and E are ornamented with lines to represent the paneled ends of the stove or range. The rear side C is extended above 25 the plane of the upper side A and is ornamented upon its front face with lines to represent the front of the elevated warming-oven and intermediate pipe or flue of a stove or range. The ornamenting-lines upon said box 30 are in white upon a black background.

I claim—

The design for a paper box substantially as herein shown and described.

In testimony whereof I affix my signature 35 in presence of two witnesses.

FRANK E. JONES.
